UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

SHEET-DELIVERY MECHANISM FOR PRINTING-PRESSES.

1,306,398.

Specification of Letters Patent. Patented June 10, 1919.

Application filed April 18, 1916. Serial No. 91,982.

To all whom it may concern:

Be it known that I, HOWARD M. BARBER, a citizen of the United States, and resident of Stonington, in the county of New London and State of Connecticut, have invented 5 a new and useful Improvement in Sheet-Delivery Mechanism for Printing-Presses, of which the following is a specification.

In printing presses where very wide webs 10 are printed, it has been found very difficult to accurately cut the web transversely by a single cutting mechanism, as for instance, by coacting rotary cutters, for the reason that it is almost impossible to keep the cutter blades from sagging; and it has also been necessary to materially slow up the travel 15 of the wide web to permit it to be cut as it passes through said cutters.

The principal object of this invention is 20 to provide means for slitting the wide web into two or more narrow webs and providing separate sheet cutting means for each narrow web, thus insuring an accurate cutting of the sheet and the cutting of the same at 25 any desired speed of the wide web.

A further object is to provide novel means 30 for delivering the sheets cut from the narrow webs. The sheet delivery more specifically includes a sheet carrier having independently operated aligned sets of grippers for taking the sheets cut from the narrow webs, and another sheet carrier having a common set of grippers arranged to take 35 the sheets and deliver them side by side.

My invention also more particularly includes the provision of means for passing 40 the narrow webs and the sheets cut therefrom through the machine in different paths without lateral movement, the cutting devices for the narrow webs being of less length than the wide web and being arranged in different transverse planes and the sheet delivery mechanism being of the full width of the wide web for delivering the 45 sheets cut from the narrow webs simultaneously and side by side.

A practical embodiment of my invention is represented in the accompanying drawings, in which—

50 Figure 1 is a top plan view of so much of a flat sheet delivery mechanism for printing presses as will give a clear understanding of my invention.

Fig. 2 is a vertical longitudinal section through the same. 55

Fig. 3 is a detail section showing certain of the gripper operating cams not shown in Fig. 2, and

Fig. 4 is a detail view of the gearing for driving the several parts. 60

The wide web 1 is passed over a slitting roll 2, where it is slit longitudinally of its travel into narrow webs; in the present instance two narrow webs, by a slitting disk 3. The two narrow webs 4 and 5 then pass 65 between the rolls 6 and 7, and the narrow web 4 is passed rearwardly and around the roll 8, while the narrow web 5 is passed forwardly and around the roll 9. Two pairs of coacting rotary cutters 10, 11, and 12, 13, are arranged in different transverse planes, the cutters 10, 11 being used to cut sheets from the narrow web 4, and the cutters 12, 13 being used for cutting sheets from the narrow web 5. 75

Means are provided for passing the narrow web 4 through the rotary cutters 10, 11, which means in the present instance, is shown as an endless carrier in which the side chains 14 which pass over the pairs of upper and lower sprockets 15 and 16 are provided with side grippers 17 carried at intervals along the same and arranged to grasp the side edges of the narrow web 4 before the web reaches the rotary cutters 10, 11, and carry the web 85 through said rotary cutters and finally direct the head of the narrow web into the guide 18. Similarly, an endless carrier comprising the side chains 19, passing over the pairs of upper and lower sprockets 20, 21, having 90 side grippers 22, is provided for carrying the narrow web 5 through the rotary cutters 12, 13, and direct the head of the narrow web into the guide 23.

The sheet delivery mechanism is herein 95 shown as comprising the rotary sheet carriers 24, 25, 26, 27, and the endless delivery carrier 28. The rotary sheet carrier 24 is provided with a set of grippers 29, arranged to transfer the sheets cut from the narrow 100 web 4, successively to the sets of grippers 30, 31, on the rotary carrier 25. Sets of grippers 32, 33, in alignment with the sets of grippers 30, 31, respectively, are arranged to take successive sheets cut from the narrow web 5. The rotary carrier 26 is pro- 105

vided with two sets of grippers 34, 35, the grippers 34 being arranged to take the heads of two sheets side by side cut from the narrow webs 4 and 5, from the alined sets of 5 grippers 30, 32, on the rotary carrier 35; and the set of grippers 35 being arranged to take the heads of two sheets side by side cut from the narrow webs 4 and 5, from the alined sets of grippers 31, 33. The rotary 10 carrier 27 is provided with a set of grippers 36 arranged to take the pairs of sheets cut from the narrow webs 4 and 5, successively from the grippers 34 and 35 of the rotary sheet carrier 26, and transfer the sheets to 15 the successive sets of grippers 37, carried by the side chains 38 of the endless delivery carrier 28, which side chains pass over the inner and outer pairs of sprockets 39 and 40. These grippers 37 of the endless delivery carrier are arranged to deposit the sheets flat and side by side upon a suitable support 41.

The side frames of the machine are denoted by 42 and 43, and the intermediate 25 short longitudinal frames by 44 and 45. The rotary cutters 10 and 11, and the means for passing the narrow web 4 through the cutters are mounted between the side frame 43 and intermediate frame 44; and the rotary 30 cutters 12 and 13, and the means for passing the narrow web 5 therethrough, are mounted between the side frame 42 and the intermediate frame 45, thus locating the cutters for the two narrow webs in different 35 transverse planes.

The rolls 2, 6 and 7 extend the full width of the wide web, and the rolls 8 and 9 extend preferably only the width of their respective narrow webs 4 and 5. The rotary 40 carrier 24 and its grippers 29, extend preferably only the width of the sheets cut from the narrow web 4, while the rotary carriers 25, 26 and 27 and the endless delivery carrier 28, extend the full width of the wide 45 web, so as to properly handle the sheets side by side cut from the two narrow webs 4 and 5.

The cams for operating the set of grippers 29 of the rotary sheet carrier 24, at their 50 receiving and transfer points, are denoted by 46, 47. The cams for controlling the operation of the set of grippers 30, 31, of the rotary sheet carrier 25, at their receiving and transfer points, are denoted by 48, 49, 55 and the cams for controlling the operation of the grippers 32, 33, of the rotary sheet carrier 25, at their receiving and transfer points, are denoted by 50, 51. The cams for controlling the operation of the grippers 60 34, of the rotary sheet carrier 26, at their receiving and transfer points, are denoted by 52, 53, and the cams for controlling the operation of the grippers 36, of the rotary sheet carrier 27, at their receiving and transfer 65 points, are denoted by 54, 55. The cams

for controlling the operation of the grippers 37, on the endless delivery carrier 28, at their receiving and delivery points, are denoted by 56 and 57. The cams for controlling the operation of the side grippers on the endless carrier which conveys the narrow web 4 through the rotary cutters 10, 11, are denoted by 58, 59, and the cams for controlling the operation of the side grippers of the carrier which conveys the narrow web 5 75 through the rotary cutters 12, 13, are denoted by 60, 61.

It will be noted, therefore, that the alined sets of grippers 30, 32, and 31, 33, are independently operated to take sheets cut from 80 their respective narrow webs.

The shaft of the slitter 3 is geared to the shaft of the roll 2, through the gears 62, 63, and the shafts of the rolls 6, 7 and 8, are driven through the gears 64, 65, 66, 67, 68. 85 The rotary cutters 10 and 11 are driven through the gears 69, 70, 71. The endless carrier for feeding the web 4, through the cutters 10, 11, is driven from the gear 72 on the shaft of the rotary cutter 11. The 90 rotary cutters 12 and 13 are driven through the gears 73, 74, 75, and the roll 9 is driven through the gears 76, 77, 78. The endless carrier for passing the narrow web 5 through the rotary cutters 12, 13, is driven through 95 the gear 79. The rotary carriers 24, 25, 26, 27, are driven through the gears 80, 81, 82, 83, and the endless delivery carrier 28 is driven through the gears 84, 85.

From the above description it will be seen 100 that by providing a separate cutting mechanism for each narrow web, the cutting mechanisms are kept within a convenient length for accurate and rapid severing of the sheets from the narrow webs.

It will also be seen that by mounting these 105 sheet cutters in different planes, the narrow webs and the sheets cut therefrom may be passed through the machine without lateral movement.

It is evident that various changes may be resorted to in the construction, form and arrangement of the various parts without departing from the spirit and scope of my invention, and hence I do not wish to limit 115 myself strictly to the structure herein set forth, but

What I claim is:

1. Means for slitting a wide web into narrow webs, separate sheet cutting devices for 120 said narrow webs, sheet gripping means for positively passing the narrow webs through their respective cutting devices, said sheet gripping means being arranged to grip the narrow webs before they reach their cutting 125 devices and to hold the webs until they pass their cutting devices and sheet gripping means for positively delivering the sheets from the first-named sheet gripping means.

2. Means for slitting a wide web into nar- 130

- row webs, separate sheet cutting devices for said narrow webs, sheet gripping means for positively passing the narrow webs through their respective cutting devices, said sheet gripping means being arranged to grip the narrow webs before they reach their cutting devices and to hold the webs until they pass their cutting devices and sheet gripping means for positively delivering the sheets 5 from the first-named sheet gripping means side by side.
3. Means for slitting a wide web into narrow webs, separate sheet cutting devices for said narrow webs, sheet gripping means for 10 positively passing the narrow webs through their respective cutting devices, said sheet gripping means being arranged to grip the narrow webs before they reach their cutting devices and to hold the webs until they pass 15 their cutting devices and sheet gripping means for positively delivering the sheets from the first-named sheet gripping means flat and side by side.
4. Means for slitting a wide web into narrow webs, separate sheet cutting devices for 20 said narrow webs, and sheet delivery means including a sheet carrier having alined independently operating sets of grippers for taking the sheets from their respective sheet 25 cutting devices and a sheet carrier having a common set of grippers for taking the sheets and delivering them side by side.
5. Means for slitting a wide web into narrow webs, separate sheet cutting devices for 30 said narrow webs, and means for delivering the sheets cut from the narrow webs side by side, said delivery means including a sheet carrier having alined independently operating sets of grippers.
- 40 6. Means for slitting a wide web into two narrow webs, separate sheet cutting devices for both of said narrow webs, and means for delivering the sheets cut from the narrow webs side by side, said delivery means including a sheet carrier having alined independently operating sets of grippers.
- 50 7. Means for slitting a wide web into narrow webs, separate sheet cutting devices for said narrow webs, and means for delivering the sheets cut from the narrow webs side by side, said delivery means including a sheet carrier having alined independently operating sets of grippers, and a sheet carrier having a common set of grippers for taking the 55 sheets from the first named carrier.
8. Means for slitting a wide web into two narrow webs, separate sheet cutting devices for both of said narrow webs, and means for delivering the sheets cut from the narrow webs side by side, said delivery means including a sheet carrier having alined independently operating sets of grippers, and a sheet carrier having a common set of grippers for taking the sheets from the first 60 named carrier.
9. Means for slitting a wide web into narrow webs, separate sheet cutting devices for said narrow webs, and means for delivering the sheets cut from the narrow webs side by side, said delivery means including a sheet carrier having alined independently operating sets of grippers, a sheet carrier having a common set of grippers for taking the sheets from the first named carrier and a delivery carrier having a common set of grippers for the sheets. 70
10. Means for slitting a wide web into two narrow webs, separate sheet cutting devices for both of said narrow webs, and means for delivering the sheets cut from the narrow webs side by side, said delivery means including a sheet carrier having alined independently operating sets of grippers, a sheet carrier having a common set of grippers for taking the sheets from the first named carrier and a delivery carrier having a common set of grippers for the sheets. 75
11. Means for slitting a wide web into narrow webs, separate pairs of rotary cutters of less length than the wide web for cutting sheets from their respective narrow webs, and sheet delivery means including a rotary sheet carrier of the full length of the wide web having independently operating alined sets of grippers. 80
12. Means for slitting a wide web into narrow webs, separate pairs of rotary cutters of less length than the wide web for cutting sheets from their respective narrow webs, and sheet delivery means including a rotary sheet carrier of the full length of the wide web having independently operating alined sets of grippers and a sheet carrier of the full length of the wide web for delivering the sheets from the narrow webs. 85
13. Means for slitting a wide web into narrow webs, separate pairs of rotary cutters of less length than the wide web for cutting sheets from their respective narrow webs, and sheet delivery means including a rotary sheet carrier of the full length of the wide web having independently operating alined sets of grippers and a sheet carrier of the full length of the wide web for delivering the sheets from the narrow webs. 90
14. Means for slitting a wide web into narrow webs, separate cutters for said narrow webs, traveling side grippers for passing the narrow webs through their cutters and traveling grippers for taking the sheets and delivering them. 100
15. Means for slitting a wide web into narrow webs, separate cutters for said narrow webs, traveling side grippers for passing the narrow webs through their cutters and traveling head grippers for taking the sheets and delivering them. 105
16. Means for slitting a wide web into narrow webs, separate cutters for said nar- 110

- row webs, traveling side grippers for passing the narrow webs through their cutters and traveling grippers for taking the sheets and delivering them side by side.
- 5 17. Means for slitting a wide web into narrow webs, separate cutters for said narrow webs, traveling side grippers for pass-

ing the narrow webs through their cutters and traveling head grippers for taking the sheets and delivering them side by side. 10

In testimony that I claim the foregoing as my invention, I have signed my name this 15th day of April, 1916.

HOWARD M. BARBER.
